UNITED STATES PATENT OFFICE.

CLARA L. K. FERGUSON, OF PHILADELPHIA, PENNSYLVANIA.

SHOE.

1,147,493.

Specification of Letters Patent.

Patented July 20, 1915.

Application filed February 12, 1915. Serial No. 7,830.

To all whom it may concern:

Be it known that I, CLARA L. K. FERGUSON, a citizen of the United States, residing in Philadelphia, Pennsylvania, have invented 5 certain Improvements in Shoes, of which the following is a specification.

My invention relates to certain improvements in a flexible dress overshoe, for which Letters Patent were granted to me on May 10 5th, 1914, and numbered 1,095,834.

The object of the present invention is to perfect and to simplify the construction of the heel portion of a shoe. This object I attain 15 in the following manner, reference being had to the accompanying drawings, in which:—

Figure 1, is a longitudinal sectional view of my improved shoe; Fig. 2, is a side view of the heel portion of my improved shoe; 20 Fig. 3, is an enlarged longitudinal sectional view of the heel portion of the shoe; Fig. 4, is a sectional view on the line *a*—*a*, Fig. 3; Fig. 5, is a sectional view on the line *b*—*b*, Fig. 1; Fig. 6, is a side view of the body 25 portion of the heel; Fig. 7, is a perspective view of the body portion of the heel; Fig. 8, is a perspective view of the outer covering section; Fig. 9, is a perspective view of the sole portion at the heel; Fig. 10, is an enlarged sectional view showing the joint between the vamp and the heel; and Figs. 11 and 12, are views illustrating modifications 30 of the invention.

Referring to the drawings, 1 is the sole of 35 the shoe in the present instance.

2 is the upper.

3 is the vamp.

The upper 2 is preferably made with an 40 open flap extending almost to the toe of the shoe, as shown at *x*, and this flap may be secured to the body of the upper by buttons, or other suitable fastenings.

The fabric I prefer to use in the vamp is 45 made of a series of rubber strands, each strand being wrapped, and these strands may form either the warp or the weft of the fabric and are held together by threads interwoven therewith. A fabric made in this manner will yield to conform to the contour 50 of the slipper or foot of the wearer and will not be affected to any appreciable extent by the heat of the foot. It is also waterproof to a certain degree.

I preferably so cut the fabric that the elastic strands will extend transversely from one 55 side to the other of the toe and vertically above the heel of the shoe. Thus the vamp can be stretched to allow for the overlapping portions of a dress slipper and a buckle, or other ornament, if worn. The 60 upper is preferably provided with an insert 4 of the yielding cloth above described with the rubber strands arranged transversely therein, which allows the insert to stretch to 65 conform to the shape of the foot of the wearer.

5 is the body portion of the heel, made as shown in Figs. 6 and 7, and having an extension 6 which forms the counter at the heel portion of the shoe above the heel proper. The forward end of the heel portion 70 of the shoe is flanged at each side, as shown at 7, and around the base, as shown at 8; the flange extending from the base to the forward edge of the heel portion which 75 extends beyond the heel proper so as to be united firmly with the sole, as shown in Fig. 5.

The sole, as illustrated in Figs. 1 and 9, has a portion 9 which extends from the heel 80 to the toe of the shoe, a vertical portion 10 which forms the front end of the heel, and a portion 11 which forms part of the base of the heel. The edge of this portion is beveled at 12 so as to extend under the beveled 85 portion of the heel section 5, as clearly shown in Fig. 3. The flange portion 7 is also preferably beveled to make a neat fit over the sole 1, as illustrated in Fig. 5. The upper edge 13 of the heel portion forms the 90 counter and is also beveled so as to make a comparatively smooth connection between the counter and the upper.

14 is the leather covering of the heel. 15 is the heel base which is secured to the heel 95 after the other parts have been assembled. 16 is the insole or lining which extends from the toe of the shoe, in the present instance, to the extreme end of the heel. The covering section 14 of the heel, which may be of 100 leather, or other suitable material, has a flange 17 at its forward end to lap over the flange 7 of the body portion of the heel and is also flanged, as at 18, so as to extend 105 under the body portion and between it and the beveled portion 12 of the heel base por-

tion, as clearly shown in Fig. 1, although it may extend, in some instances, between the heel portion 11 and the heel base 15.

One of the main features of the invention 5 is to make a neat fit at the upper edge of the heel covering where it unites with the fabric of the vamp. This is accomplished by forming a groove 19 in the body portion of the heel, as shown in Figs. 3, 4 and 6, and the 10 lower edge of the fabric of the vamp extends into this groove, as shown in said figure, and is secured therein.

The upper edge 20 of the heel covering 14 is turned over as illustrated in Fig. 10, and 15 is also secured in the groove. By this construction no raw edge of the fabric or leather is exposed to wear and, as the outer line of the heel at the joint is practically continuous, the shoe is neat and attractive in 20 appearance. The body of the heel, in the present instance, is comparatively stiff but has a certain amount of elasticity, the same as the ordinary counter of a shoe and it can be made of any thickness, according to the 25 desire of the manufacturer, as, in some instances, a comparatively stiff and substantial heel will be required, while in other instances the heel may be made flexible.

The lining 24 of the shoe extends into the 30 hollow heel, as shown in Figs. 3 and 4, so that the inside of the shoe is smooth and a foot with a slipper thereon can be readily inserted in the shoe. I preferably run a line of stitches 21 beyond the upper edge of 35 the body portion of the heel so as to hold the parts in position, and I secure the lower portion of the lining in the heel in any suitable manner.

In some instances a line of stitches 22 may 40 be made directly above the groove 19 to attach the fabric to the body of the heel, as in Fig. 12, to relieve the joint at the groove from strain, or stitches 23 may be at the 45 groove, as in Fig. 11, supplementing the cement or taking the place of the cement.

I claim:

1. The combination in a shoe, of a body portion forming the heel and the counter, the body portion having a groove formed 50 therein around the base of the counter; a vamp section; and a covering inclosing the side and rear end of the heel and terminating in the groove.

2. The combination in a shoe, of a sole; 55 a hollow body forming the heel proper and the counter, the exterior surface of the body portion having a groove therein around the base of the counter; a vamp section terminating within the groove; and a covering 60 for the sides and rear end of the heel having its upper margin folded under and located in the groove.

3. The combination in a shoe, of a hollow heel, the body portion of the heel having an 65 extension forming a counter; a vamp sec-

tion extending over the counter and secured to the body portion at the upper edge of the heel proper; and a lining for the vamp extending into the hollow heel.

4. The combination in a shoe, of a hollow 70 heel, the body portion of the heel having an extension forming a counter; a vamp section extending over the counter and secured to the body portion at the upper edge of the heel proper; a lining for the vamp extending 75 into the heel; and a row of stitches above the upper edge of the counter and securing the lining to the vamp.

5. The combination of a hollow heel section forming a counter and the heel proper, 80 said section having an inturned flange at the lower edge and having flanges at the forward end of the heel; a sole section bent and forming the front end of the heel and having a portion extending under the flange 85 at the lower edge of the heel; a lining extending over the full interior surface of the heel at the front and bottom; a covering for the sides and rear end of the heel having an inturned flange at its lower edge; and a base 90 secured to the bottom of the heel.

6. The combination in a shoe, of a hollow heel section forming the heel proper and the counter, said heel section having an inturned flange at the base and at the forward end, 95 said flange extending forward of the heel, the flange being tapered; and a sole section extending under the body of the shoe and bent at the rear to form the front of the heel and having a tapered portion overlapping the flange at the base of the heel section.

7. The combination in a shoe, of a hollow heel section forming a heel proper and counter, and having a tapered flange at the 105 base and at the forward end and also having an external groove extending on each side and at the back on a line with the lower edge of the vamp; a sole section extending to and forming the front section of the heel; a vamp secured to the sole and having its lower edge at the heel located within the groove in the heel section; and a covering for the sides and rear end of the heel having its upper edge also located within the groove. 110

8. The combination in a dress overshoe having a hollow heel, of a sole section extending under the body of the shoe and extending to and forming the front of the heel and a portion of the base of the heel; a hollow body portion forming the sides of the heel proper and the counter and beveled at its upper edge and also having a beveled flange at the bottom and front end and having a groove in the exterior thereof forming 125 the upper line of the heel proper; an upper and a vamp secured to the sole and having its lower edge located within the groove of the heel section; a heel covering having an undeturned portion at its upper edge also 130

located within the groove and having a flange at its lower edge; a heel base; and an inner sole or lining extending over the inner surface of the front portion of the heel and

5 the bottom thereof.

In testimony whereof, I have signed my

name to this specification, in the presence of two subscribing witnesses.

CLARA L. K. FERGUSON.
